UNITED STATES PATENT OFFICE

2,437,130

ULTRA HIGH FREQUENCY ELECTRIC
DISCHARGE DEVICE

William J. Scott and Christopher J. Milner,
Rugby, England, assignors to General Electric
Company, a corporation of New York

Application October 6, 1944, Serial No. 557,451
In Great Britain July 3, 1942

Section 1, Public Law 690, August 8, 1946
Patent expires July 5, 1963

3 Claims. (Cl. 250—27.5)

1

This invention relates to ultra high frequency systems employing an electron discharge oscillator having a cavity resonator and it has for its object to provide an improved arrangement for abstracting energy from such a resonator.

This invention relates more particularly to an improved coupling of an output line to the resonator of an electron discharge oscillator of the velocity modulation type employing an envelope wholly or partly of metal and in which the resonator forms part of the bulb or can of the electron discharge device and the concentric output line has its outer conductor passing through the stem or header closing one end of the envelope. In such a construction, the end of the concentric line bears a loop which enters a hole in the resonator.

In such constructions as have hitherto been adopted, the termination of the outer conductor at the output line of the resonator has not been such as to exclude leakage of resonant power at the joint with resultant loss of efficiency.

The present invention consists in eliminating all possibility of leakage of resonant frequency field between the end of the outer conductor of the output concentric line and the resonator hole by providing an overlapping joint, not entering the resonator, between the outer conductor and the wall so that, when the header is assembled to the metal envelope, as by welding, there is a relatively tight joint between the outer conductor and the resonator.

Further to improve this joint, a low melting point metal, such as tin, may be placed in or around the joint so that during exhaust the tin melts and makes a soldered joint.

For a better understanding of the invention, reference may be had to the following description taken in connection with the accompanying drawing in which the single figure is a cross-sectional longitudinal view of an electric discharge device of the velocity modulation type built in accordance with the invention.

Referring particularly to the arrangement shown in the drawing, we have there illustrated the invention as applied to a reflex oscillator comprising an electron gun 1, a cavity resonator or chamber 2, and a reflector electrode 3. The electron gun 1, which comprises an emissive cathode surface 4' heated by a suitable filamentary heater 4 and is surrounded by an electrode 5 for suitably concentrating the electrons into a beam, is supported by lead-in conductors 6 and 7 which pass through glass-to-metal eyelet seals 8 in a metal header 9 which closes the lower end of the lower

2

part 10 of the envelope of the device. The upper wall 11 of the part 10 forms a lower wall of the cavity resonator 2 which is completed by a flanged metal plate 12 secured to the wall 11, as by welding, and which contains a centrally located aperture 13 through which an electron beam from the electron gun 1 passes. A metallic tubular member 14 is secured to the upper wall 11 in alignment with the aperture 13 to define with the metal plate 12 a narrow gap 15 in the cavity resonator 2 which is traversed by the electron beam projected from the gun 1. Upon the metal plate 12 is, in turn, mounted a flanged plate 16 through an aperture in which is led by an eyelet seal 17 a lead-in wire 18 supporting the reflector electrode 3.

In the operation of the electric discharge device of the velocity modulation type thus far described, the electron beam emanating from the gun 1 and accelerated by the anode or resonator structure 2 is velocity modulated periodically as it traverses the velocity modulating gap 15 by the variation in the electromagnetic fields thereacross, so that successive groups of electrons are alternately accelerated and decelerated, tending to group the electrons in the beam after the beam has traversed the velocity modulation gap. After undergoing this velocity modulation, the electrons are reversed in direction of travel by the electrode 3 and re-enter the cavity resonator delivering energy to the electromagnetic field thereof. Oscillations at the resonant frequency of the resonator 2 appear therein and are abstracted therefrom by an output lead which usually consists, in view of the ultra high frequency of such oscillations, of a concentric line 19, the inner conductor of the line terminating within the resonator 2 in a loop 20. The outer conductor 21 is secured at its lower end to the inside of the header 9 and is continued exteriorly by an extension 22, the inner conductor passing through the header by way of a glass-to-metal eyelet seal 23. The free end of loop 20 is secured to the inner surface of outer conductor 21 at the point 20' in any suitable manner, such as by welding.

Leakage of radio frequency power may readily occur between the upper end of conductor 21 and the aperture 24 in the wall of cavity resonator 2 through which the loop 20 extends. It is not generally possible to make an effective seal at this point when the wall portion 10 with its attached part is presented to the header 9 for sealing thereto. To avoid this difficulty, according to the present invention, we eliminate all possibility of leakage of electromagnetic field between the end

of the conductor 21 and the wall 11 of resonator 2 by providing an overlapping joint, not entering the cavity, between the outer conductor 21 and the wall 11. As shown in the drawing, a flanged member or eyelet 25 is secured, as by welding, to the lower surface of the resonator wall 11 around the aperture 24 and, during assembly of the part 10 and header 9, the conductor 21 is inserted into the eyelet 25 so as to make a relatively close fit therewith. The joint may be further improved by placing a low melting point metal, such as a ring 26 of tin, in or around the joint so that, during the heating which accompanies the exhaust process, the tin melts and forms a soldered joint. A tabulation 27 depending from header 9 and communicating with an aperture 28 in that header provides means whereby the device may be evacuated or exhausted.

Alternatively, the eyelet 25 may be secured to conductor 21 and the butt joint between the eyelet and the resonator wall 11 formed during the assembly. The upper end of the conductor 21 may be flanged in place of providing a separate eyelet, the flange abutting against the resonator wall.

As a further alternative, the wall of the resonator may be downwardly flanged around the aperture 24 for loop 29 and the conductor 21 inserted into the flange during assembly. If the cavity resonator is formed by producing a cavity in a relatively heavy block of metal and attaching a thin diaphragm in the cavity to complete it, as described in the copending application of William J. Scott, Richard G. Saunders, and Robert Latham, Serial No. 557,452, filed October 6, 1944, and assigned to the assignee of the present invention, an overlapping joint between conductor 21 and the thick wall of the cavity resonator is provided if the conductor 21 extends to and closely fits within the aperture 24 for the reception of the loop 29.

Although, in the drawing, practically the whole wall of the electric discharge device is shown as of metal, this construction is not essential. The leads supporting the electron gun may extend through a glass stem sealed to a glass portion which is, in turn, ring sealed to the wall portion 10.

While we have shown and described a particular modification of our invention, it will be obvious to those skilled in the art that many changes and modifications may be made without departing from the invention and we therefore aim in the appended claims to cover all such changes and modifications as fall within the true spirit and scope of the invention.

What we claim as new and desire to secure by Letters Patent of the United States is:

1. An electron discharge device of the velocity modulation type having a cavity resonator integral therewith and a header terminating one end of said device, said resonator including a wall having an opening therein, a concentric output

transmission line extending through said header and coupled to said resonator through said opening, said line having an outer conductor extending into proximity with said opening and a centrally disposed inner conductor, said inner conductor extending into said resonator and having one end secured to said outer conductor whereby assembly of said device is facilitated, and means for preventing leakage of electro-magnetic fields between said outer conductor and said resonator comprising an annular flange surrounding said outer conductor and said opening in closely fitting relationship to said outer conductor and said wall.

15 2. An electron discharge device of the velocity modulation type having a cavity resonator integral therewith and a header terminating one end of said device, said resonator including a wall having an opening therein, a concentric output transmission line extending through said header and coupled to said resonator through said opening, said line having an outer conductor extending into proximity with said opening and a centrally disposed inner conductor, said inner conductor extending into said resonator and having one end secured to said outer conductor whereby assembly of said device is facilitated, and means for preventing leakage of electro-magnetic fields between said outer conductor and said resonator comprising an annular flange external to said resonator surrounding said outer conductor and said opening in closely fitting relationship to said outer conductor and said wall.

25 3. An electron discharge device of the velocity modulation type comprising an envelope for said device, a cavity resonator within said envelope, a header terminating one end of said envelope at a point spaced from said resonator, a concentric output transmission line comprising an outer conductor which passes through said header and an inner conductor which projects into said resonator, means for preventing the leakage of electromagnetic field between said outer conductor and said resonator, said means comprising a flange attached to said resonator and forming an overlapping joint with said outer conductor, said joint being wholly external to said resonator, and means sealing said joint comprising a low melting point metal disposed between said flange and said outer conductor.
